Fig. 2

The design of this invention is applied to a one-piece tray of rectangular perimeter having a series of longitudinal rows of cups separated by wavy partitions and is characterized by oblique ribs of rounded cross section extending inwardly from the corners of the tray, each rib having rounded grooves on opposite sides thereof, and by aligned rounded notches in the lateral partitions of each outer row of cups, all as shown.

I claim:

The ornamental design for a compartmented tray as shown and described.
